MAURICE BARNETT AND LOUIS BURGESS, OF NEW YORK, N. Y., ASSIGNEES TO
ALCHLOR CHEMICAL COMPANY, A CORPORATION OF DELAWARE.

ART OF PRODUCING ALUMINUM CHLORID.

1,218,588.

Specification of Letters Patent.

Patented Mar. 6, 1917.

Application filed August 14, 1916. Serial No. 114,813.

To all whom it may concern:

Be it known that we, MAURICE BARNETT and LOUIS BURGESS, citizens of the United States, residing at New York, in the county 5 of New York and State of New York, have invented or discovered certain new and useful Improvements in the Art of Producing Aluminum Chlorid, of which the following is a specification, reference being had there- 10 in to the accompanying drawing.

This invention or discovery relates to the art of producing anhydrous aluminum chlorid (Al_2Cl_6), and has for its object the production of this substance at less expense 15 than is involved in the production thereof by processes heretofore in use. In practising the present invention or discovery aluminum carbid is treated with dry hydrochloric acid gas in a retort at a temperature 20 sufficiently high to effect conversion of the aluminum carbid into aluminum chlorid and volatilization of the latter, and the volatilized aluminum chlorid is then conducted to a condenser or condensers in which aluminum chlorid will be deposited, and from 25 which certain gas or gases, resulting from the conversion of the aluminum carbid into aluminum chlorid, will be conducted or allowed to escape. Instead of thus treating 30 aluminum carbid alone with dry hydrochloric acid gas in the presence of heat, aluminum carbid and metallic aluminum may be thus treated, in the production of anhydrous aluminum chlorid.

The accompanying drawing illustrates an apparatus by which the present invention or discovery, as thus generally stated, may be carried into effect, although it will be understood that said invention or discovery 40 may be practised by means of any suitable apparatus.

Referring to the drawing, 12 denotes a furnace which may be made of iron and brick or other suitable material, and which 45 will preferably be lined with some refractory substance. Within the furnace 12 is a retort 14 of any suitable refractory material and within which the aluminum carbid, or aluminum carbid and metallic aluminum; 50 to be treated will be placed, and in which retort it will be subjected to the action of

dry hydrochloric acid gas which may be introduced into the lower part of the chamber of the retort through a pipe 15 preferably provided with a valve 16 by which the 55 flow of gas to the chamber of the retort may be regulated. Air and moisture will be excluded from the retort and condensers as far as possible. The furnace and retort may be heated in any suitable manner, as 60 by means of oil firing and auxiliary gas burners 13.

The chamber of the furnace 12 is preferably provided at its upper part with a receptacle 17 having a charging hopper 18 provided with a movable cover 19, and in this receptacle 17 the aluminum carbid, or aluminum carbid and metallic aluminum, may be heated prior to being introduced into the retort 14. The ledge or shelf 12^a which supports the charging receptacle 17 is provided with flue openings 12^c, denoted by dotted lines. The chamber of the receptacle 17 is provided at its bottom with a sliding gate 21 beneath which is a charging hopper 20 70 for the retort 14, said charging hopper 20 being provided at its bottom with a sliding gate 22. By opening the sliding gate 21 a suitable amount of heated material may be dropped into the charging hopper 20 from 75 whence it will fall into the retort 14 when the sliding gate 22 is opened. These sliding gates are provided with handles 21^a and 22^a, respectively, by which they may be operated through openings in the wall of the furnace 80 and which openings may be closed by drop- doors 12^a, or otherwise.

The furnace 12 is provided near its top with a pipe 23 leading to a suitable stack or chimney, and the said furnace is provided at its lower part with an opening 24 opposite the bottom of the retort which is provided with a corresponding opening 25. These openings may be closed in any suitable manner, as by a stopper 26 of refractory 90 material and which stopper may be removed when access to the chamber of the retort is desired for the purpose of removing the spent or nearly spent material. The furnace and retort walls may be provided with 95 peep-holes, if desired, and is common with furnaces and retorts.

Leading from the upper part of the chamber of the retort 14 is a duct 27 through which the volatilized material may be conducted from the said retort to the chamber 5 of a condenser and thence preferably to a second, third or fourth condenser; or instead of several condensers a single condenser, preferably having several chambers, may be used. The condenser 28 shown in 10 the drawing may be considered to be the last one of the series, when several condensers are used, and in such case the first condenser should be close to the furnace 12 and the other condensers of the series close 15 to or in juxtaposition with each other. Each condenser, or condensing chamber, will preferably be provided at its upper part with a baffle plate 29 against which the volatilized material will impinge as it enters the condensing chamber. The baffle plate 29 may 20 be mounted in any suitable manner in the upper part of the condenser. Also each condenser is preferably provided at its top with a man-hole closed by a stopper or cover 25 30, and other man-holes 31 in the lower parts of the condensers, and which afford access to the lower parts of the chambers thereof, are closed by suitable stoppers or covers 32. Also each condenser or condensing chamber is preferably provided at its 35 bottom with a hinged door 33 which may be opened downwardly when the aluminum chlorid deposited in a condenser or condensing chamber is to be removed. The hinged door 33 may be held closed by a spring catch 35. The condensers may, for convenience, be mounted on an arch or arches, as 34.

In the conversion of the material within 40 the retort 14 into aluminum chlorid a combustible gas is evolved, and such gas may be conducted from the upper part of the chamber of the last condenser to the burners 13 by a suitable pipe, 13^a, which will 45 preferably be provided with a valve 13^b, thus utilizing this gas as a heating medium supplemental to other heating means; or if it be not desired to utilize this combustible gas for heating the furnace 12, or for 50 other economic purposes, it may be allowed to escape from the chamber of the last condenser in any suitable manner. The burners 13 will preferably be provided with pilot lights by which they may be readily 55 ignited, and which will avoid any danger of explosion by an accumulation of any gas which may accidentally escape from the burners.

While it is deemed preferable to subject 60 the aluminum carbid, or aluminum carbid and metallic aluminum, to a dull red to yellow heat (preferably from about 600° to 900° C.) when being treated by the hy-

drochloric acid gas, and while it is considered preferable, in order to expedite the 65 volatilization, to previously heat the material to be treated in the receptacle 17, the invention is not to be understood as being limited to these temperatures, in treatment, or to a previous heating of the material to 70 be treated by the hydrochloric acid gas, as the gas itself may be highly heated before being introduced into the retort 14, in carrying the invention into effect. It will be understood, however, that the conversion 75 of the aluminum carbid, or aluminum carbid and metallic aluminum, into aluminum chlorid will be more readily effected by heating the material itself, rather than the hydrochloric acid gas; and it will also be 80 understood that at a higher temperature the operation will be more rapid than at a lower temperature.

In practising the invention as hereinbefore described anhydrous aluminum chlorid 85 can be produced at less expense than by the processes by which this material has heretofore been produced.

Having thus described our invention or discovery we claim and desire to secure by 90 Letters Patent:

1. The herein described process for producing aluminum chlorid, consisting in 95 treating aluminum carbid with hydrochloric acid gas in the presence of heat.

2. The herein described process for producing aluminum chlorid, consisting in treating aluminum carbid with hydrochloric acid gas in the presence of heat, and subsequently condensing the volatilized aluminum chlorid thus produced. 100

3. The herein described process of producing aluminum chlorid, consisting in 105 treating aluminum carbid with hydrochloric acid gas in a heated retort within a furnace, thereby producing volatile aluminum chlorid, then condensing the volatilized chlorid and heating said furnace by conducting thereto and burning therein a combustible gas evolved in said process. 110

4. The herein described apparatus for use in producing aluminum chlorid, consisting of a furnace, a retort in said furnace, a charging receptacle in said furnace above 115 said retort, a condenser to which the volatilized aluminum chlorid is conducted from said retort, a gas burner or burners for heating said furnace, and means for leading a combustible gas, evolved during the production of the aluminum chlorid, from said condenser to said burner or burners. 120

5. The herein described apparatus for use in producing aluminum chlorid, consisting of a furnace, a retort in said furnace, a charging receptacle in said furnace above 125 said retort, a condenser to which the vola-

tilized aluminum chlorid is conducted from said retort, a hopper between said receptacle and retort, sliding gates at the bottoms of said receptacle and hopper, a gas burner or burners for heating said furnace, and means for leading a combustible gas, evolved during the production of the aluminum chlorid,

from said condenser to said burner or burners.

In testimony whereof we affix our signatures.

MAURICE BARNETT.
LOUIS BURGESS.
